UNITED STATES PATENT OFFICE.

ELIAS DURLACH, OF BROOKLYN, NEW YORK.

TOY STOVE.

SPECIFICATION forming part of Letters Patent No. 272,664, dated February 20, 1883.

Application filed July 27, 1882. (No model.)

To all whom it may concern:

Be it known that I, ELIAS DURLACH, a citizen of the United States of North America, and a resident of Brooklyn, county of Kings, 5 State of New York, have invented a new and useful Improvement in Toy Stoves, of which the following is a specification.

In the construction of tin toy stoves, the opening for the grate or fire place is ordinarily made 10 by cutting out and removing a piece of the metal of the dimensions of the opening from the stove-front; and a grate is then made of a piece of tin larger than said opening, cut and bent in proper shape, and soldered by its upper edge 15 on the inside of the stove-front. This method or form of construction is, however, faulty, because involving an unnecessary waste of metal and solder and increased labor, and because the grate quickly becomes detached in use.

20 The object of my invention is to avoid these objectionable features; and it consists of a grate forming an integral portion of the stove itself.

Reference is to be had to the accompanying 25 drawings, forming part of this specification, in which similar letters of reference indicate corresponding parts in all the figures.

Figure 1 is a front elevation of a toy stove showing my invention. Fig. 2 is a reduced 30 perspective view of a stove-front, showing my invention in reverse. Fig. 3 is an enlarged section on line $\alpha\alpha$, Fig. 2.

In the drawings, A represents a tin toy stove, and A' the front thereof.

To form the grate B two vertical parallel 35 cuts, aa , and a horizontal connecting-cut, b , are made in the central portion of the front A'. Then the grate-bars c are formed in said partly cut-away central portion by cutting out and removing alternate vertical strips, leaving the 40 spaces d alternating with the bars c , which latter are connected at their lower ends by a strip, f , that is also permitted to remain. Then the lower part of the central portion of the front A' is bent upward and inward, as shown, thus 45 forming a grate, B, which is attached along its upper edge to the stove-front A', and forms an integral portion thereof.

Having thus described my invention, I claim as new and desire to secure by Letters Patent— 50

A toy-stove grate constructed substantially as herein shown and described, and forming an integral portion of the stove, as set forth.

In testimony that I claim the foregoing as my invention I have signed my name, in presence of two witnesses, this 19th day of July, 55 1882.

ELIAS DURLACH.
